UNITED STATES PATENT OFFICE.

EBENEZER McLANE, OF GALENA, KANSAS.

SHOT-PROOF STRUCTURE FOR CARS.

SPECIFICATION forming part of Letters Patent No. 426,949, dated April 29, 1890.

Application filed January 10, 1890. Serial No. 336,496. (No model.)

To all whom it may concern:

Be it known that I, EBENEZER McLANE, a citizen of the United States, and a resident of Galena, in the county of Cherokee and State 5 of Kansas, have invented certain new and useful Improvements in Forts to be Used in Railway-Cars; and I do hereby declare that the following is a full, clear, and exact description of the invention, which will enable 10 others skilled in the art to which it appertains to make and use the same.

My invention relates to improvements in forts or similar structures designed to be used in connection with express and other cars as 15 refuge for the person in charge of the car against the attacks of train-robbers, and from which he can successfully defend himself without liability of being injured.

The frequency of railroad-train robberies 20 and the injuries and indignities suffered by express-messengers in defending the property intrusted to their care render it essential and necessary that some means should be provided or a refuge constructed in which the 25 agent, messenger, or other person in charge could find a shelter in times of attack and from which he could resist the onslaughts of the robbers.

The object of the invention is to provide a 30 fort or structure of bullet-proof material provided with suitable port-holes, and so constructed, located, and arranged within the car that in times of attack the person in charge can fasten himself securely therein, 35 so that he cannot be reached or dislodged by ordinary means, and from his place of safety can direct a fire upon the robbers through the port-holes without any danger of being injured in return.

40 The invention consists in the novel construction and combination of parts hereinafter fully described, and then definitely pointed out in the claims.

In the accompanying drawings, Figure 1 45 represents a perspective view of one end of an ordinary express-car with my improved fort or safety-inclosure located therein. Fig. 2 is a vertical sectional view of the fort. Fig. 3 is a plan view of the same.

50 In the said drawings, the reference-numeral 1 designates the floor of the car, 2 the end thereof, and 3 one of the sides.

The numeral 4 designates the base of the fort or structure, consisting of four sides, forming a square housing or inclosure and 55 provided with a door 5, opening outwardly into the interior of the car. The edges of this door are inclined or beveled, so as to prevent its being forced inward, the door-frame being correspondingly beveled for this 60 purpose, and is provided with suitable locks or other fastening devices.

The structure is made of sheet metal, (preferably steel,) so as to be bullet-proof, and all joints are protected by angle-irons 6, secured 65 by means of rivets. At the top the base portion flares outwardly, forming an octagonal or eight-sided beveled or inclined wall 7, to which is secured the upwardly-projecting portion 8. The wall 7 and portion 8 are of 70 the same material as the base portion to which they are riveted or otherwise secured, the joints being protected by angle-irons, as in the base portion. In the inclined wall 7 are formed a number of port-holes 9, closed by 75 means of outwardly-swinging hinged doors 10, which are held in their closed position by means of springs 12 secured thereto and to said wall.

For the purpose of preventing the door 80 from being pried open a series of metallic strips 13 are riveted around the door-frame, forming a projecting protecting-flange which entirely surrounds the door when closed, rendering it exceedingly difficult to insert a jimmy 85 or other tool or implement to force the door open.

The structure is located in one corner of the car, with a part of the upper portion 8 and wall 9 with its port-holes projecting over the 90 sides and one end of the car, so that the occupant of the structure can direct his fire upon parties outside of the car as well as inside. It will be understood from the foregoing that in case of an attack the agent or 95 messenger will fasten himself within the fort, where, out of reach of the robbers, he can defend the property intrusted to his care.

I am aware that it is not new to construct a fort or other similar bullet-proof structure 100 within a railroad-car, so that the express-agent can take refuge in said structure in times of attack by train-robbers and from the interior thereof direct a fire upon the robbers both in-

side and outside the car; and such I do not broadly claim.

Having thus described my invention, what I claim is—

- 5 1. The combination, with an express-car, of a bullet-proof structure consisting of a base portion 4, inclined octagonal wall 7, provided with port-holes 9, the upper portion 8, and the door 5 in the base portion, a section of 10 said upper portion and inclined wall extending outside of and projecting over the sides and end of the car, substantially as described.
- 15 2. The combination, with an express-car, of a bullet-proof structure consisting of a base portion 4, having a door 5, the edges of which

are beveled, the door-frame having corresponding bevels, and the strips 13 secured around said door-frame, the inclined octagonal wall 7, having port-holes 9, doors 10, and springs 12, and the upper portion 8, secured to said wall 7, all constructed and located substantially as and for the purpose described. 20

In testimony that I claim the foregoing as my own I have hereunto affixed my signature in presence of two witnesses.

EBENEZER McLANE.
